HAMBURGER PATTY-FORMING DEVICE

George J. Federighi and Richard D. Coffman,
San Francisco, Calif.

Application March 6, 1939, Serial No. 260,058

2 Claims. (Cl. 107—15)

Our invention relates to improvements in a hamburger patty-forming device, and it consists of the combinations, constructions and arrangements hereinafter described and claimed.

5 It is difficult to properly form hamburger into a patty by hand and to make it of uniform thickness throughout and of a perfect circumference. Usually a hamburger patty made by hand is thin at certain portions of its circumference and these 10 portions will burn before the main body of the patty is cooked. It also takes time to properly form a patty by hand.

The principal object of our invention is to provide a hamburger patty-forming device which 15 will quickly form a predetermined quantity of hamburger into a patty of a uniform thickness and a perfect circle in size.

Other objects and advantages will appear in the following specification and the novel features 20 of the device will be particularly pointed out in the appended claims.

Our invention is illustrated in the accompanying drawing forming a part of this application, in which

25 Figure 1 is a front elevation of the device; Figure 2 is a side elevation, partly in section;

Figure 3 is a bottom plan view of the patty-forming dies, taken along the line 3—3 of Figure 2;

30 Figure 4 is an enlarged side elevation of a portion of the rotating die; and

Figure 5 is a sectional view through the dies showing them in operative position for forming a patty.

35 In carrying out our invention, we provide a base 1 on which a casing 2 is mounted. The casing supports a motor 3 and the motor in turn carries a gear reduction housing 4. A shaft 5 projects through the housing and is slidably 40 keyed to a worm gear 6. The worm gear meshes with a worm 7 that is mounted on a motor shaft 8.

A two piece hamburger patty-forming die is removably secured to the lower end of the shaft

45 5. A rotatable die member A has a shank 9 receivable in a bore 10 in the shaft 5 and a key 11 is passed through aligned openings in the shaft and shank for securing the parts together. A disc 12 is carried by the lower end of the shank 50 and has its undersurface grooved in a manner hereinafter described.

A non-rotatable die B comprising a housing 13 is slidably mounted on the shank 9 and shaft 10. When the shaft 5 is in raised position, the disc 55 12 will bear against a washer 14 and will lift the

non-rotatable die B above the base 1. The die B will hang loosely on the disc 12 and has a circular flange 15 that contacts with the periphery of the disc 12. The flange carries an outwardly extending lug 15a that slidably contacts with a pin 16 mounted in the casing 2. The die housing 13 has its top perforated at 17 to permit vertical movement between the two dies A and B without building up air pressure or creating a vacuum in the top of the die B.

The shaft 5 is slidably mounted in the housing 4 and a spring 18 bears against the housing and against a cap 5a pivoted to a lever 19 for yieldingly holding the two-piece die above the base 1. A link 20 connects the lever to the housing 4. A downward movement of the lever 19 will compress the spring and move the two-piece die toward the base until the die B comes to rest on the base. Further movement of the lever will move the rotating die A downwardly in the housing die B.

Before describing the operation of the device, it is best to refer to Figure 3 where the bottom plan view of the rotating die A is shown. The bottom of the die has spiral grooves 21 therein of a cross sectional shape as shown in Figure 4. The leading edge of the groove has a shoulder extending substantially at right angles to the bottom face of the die, while the rear edge of the groove slopes gradually from the front edge and merges into the plane of the die bottom. The purpose of making the grooves spiral is to force the hamburger outwardly toward the flange 15 as the die A is rotated. The grooves will smooth out the upper surface of the patty as they move the hamburger toward the flange 15 and this is due to the gently curving rear edges of the grooves. Moreover, the gently curving rear edges will permit air to enter between the bottom of the die and the hamburger with the result that any suction between the hamburger and the die bottom will be broken and the die will lift clear of the hamburger when the lever 19 is freed.

From the foregoing description of the various parts of the device, the operation thereof may be readily understood. A paper 22 with a quantity of hamburger is placed under the double die. The motor will rotate the die A about 90 revolutions per minute due to the gear reduction, although we do not wish to be confined to any particular speed. The die B is held against rotation by the lug 15a and pin 16. The lever is manually moved downwardly until the housing die B covers the hamburger. Further

downward movement of the lever will bring the rotating die A down upon the meat and the spiral grooves 21 will spread the meat toward the flange. The handle 19 is continued in its 5 downward movement until a certain back pressure is developed which will indicate to the operator that the meat has been spread to a uniform thickness within the die housing B. The shaft 5 rotates in a cap 5a that in turn is pivotally connected to the lever 19 at 19a. The 10 spring 18 is fully expanded when the disc 12 and housing 13 are raised above the base 1 as shown in Figures 1 and 2.

The handle or lever 19 is now freed and the 15 perfectly formed patty will remain on the paper while the spring 18 raises the double die. The patty will have a periphery of a perfect circle and the thickness of the patty will be uniform throughout. Another quantity of meat may be 20 brought into registration with the double die and the operation repeated. The device materially speeds up the proper forming of hamburger patties and gives a uniform product at all times. It is especially adapted for restaurant use or at 25 hamburger stands where a large quantity of hamburger patties must be made in a short time.

While we have shown only the preferred form 30 of our invention, it should be understood that various changes or modifications may be made within the scope of the appended claims without departing from the spirit of the invention.

We claim:

1. In combination, a base for supporting a 35 quantity of hamburger, a rotating shaft, a disc carried by the shaft and rotatable therewith,

means for moving the shaft and disc toward the base for causing the disc to flatten the hamburger into a patty, a circular cup-shaped housing slidably telescoping over the disc with the rim of the housing depending below the latter 5 and enclosing the disc, said housing receiving the hamburger when the housing is lowered, said disc being movable with respect to the housing for forcing the hamburger against the circular housing wall for forming a patty of 10 uniform thickness and perfect circumference, the disc being arranged to raise the housing above the base when the shaft is retracted, and means for holding the housing against rotation at all times during its movement toward and 15 away from the base, whereby the housing will be retained against turning as it is moved relative to the base.

2. In a device of the type described, a double 20 die for forming hamburger patties, one die being in the shape of a circular cup-shaped housing, means for raising this die above a support and for lowering it onto the support, means for preventing rotation of this die at all times during its movement toward and away from the 25 support, whereby the cup-shaped die will be retained against turning as it is moved relative to the support, the other die being rotatable in the first die and movable axially with respect to the first die, the means for raising the first die 30 also moving the second die axially, and means for rotating the second die for forming a patty on the support and confined within the two dies.

GEORGE J. FEDERIGHI.

RICHARD D. COFFMAN.
